ABRASIVE ELEMENT

William J. Ellis, Cleveland, Ohio

Application July 18, 1929. Serial No. 379,246

3 Claims. (Cl. 51—196)

The present invention, relating, as indicated, to an abrasive element, is particularly directed to a tubular abrasive element or so-called sleeve and to a new improved and more economical method of manufacturing the same. The principal object of the invention is the provision of a simple and inexpensive sleeve and the method of making same which shall be very much more simple and shall at the same time produce a 10 very much stronger sleeve than those now in general use.

To the accomplishment of the foregoing and related ends, said invention, then, consists of the means and steps hereinafter fully described 15 and particularly pointed out in the claims; the annexed drawing and the following description setting forth in detail certain means and one mode of carrying out the invention, such disclosed means and mode illustrating, however, but one of 20 various ways in which the principle of the invention may be used.

In said annexed drawing:—

Fig. 1 is a view in perspective of my improved abrasive element; Fig. 2 is a plan view of a sleeve 25 of abrasive coated fabric for use in making the sleeve of Fig. 1; Fig. 3 is a section on the line 3—3, Fig. 2; Fig. 4 is a side elevation of a formed sleeve; and Fig. 5 is a view in perspective of a modification of my improved sleeve.

30 An abrasive sleeve consists of a hollow tubular element formed of a layer of suitable supporting material, such for example as fabric or some kind of paper stock, the outer surface of which is coated with an adhesive and a layer of abrasive. These sleeves are put to numerous uses, being formed in various sizes and being employed in surfacing convex portions of metal and wood panels, castings and the like, while smaller sleeves 35 are used for many other purposes, such for example as the grinding down of very small castings of precious and semi-precious metals and for the finishing of small objects of porcelain or similar materials.

My improved sleeve consists, briefly stated, of 45 a spirally wrapped sheet of abrasively coated material which has the advantage of being capable of rapid and continuous production, and the further advantage of having a very much improved engagement between adjacent edges or sides of 50 the material employed. In producing this sleeve I first take a strip 1, consisting of a backing sheet 2, here shown as of fabric, coated with a layer of abrasive 3 secured to the backing by a layer 55 of adhesive 4. The adhesive and abrasive are applied over a portion of the surface only, ex-

tending from the edge 5 to a line 6 parallel with the edges 5 and 7 of the strip. It is immaterial as to whether the uncoated portion 8 of the strip 1 is first coated with abrasive and the abrasive then removed or is in some way left uncoated 60 during the coating operation applied to the initial sheet.

The strip 1 I then wrap spirally upon itself, this operation being performed either manually or by suitable machines in such a way as to cause 65 the coated portion of the sheet to overlap and engage against the uncoated portion of the sheet 8. The process is substantially that of twisting a paper strip about itself to form a spiral tube, except that the coated abrasive strip is here so 70 wrapped that it engages only over the uncoated portion of the sheet, thus providing a substantially smooth unbroken surface of abrasive on the outer surface of the resulting tube.

In Fig. 4 I have shown the abrasive strip 1 so 75 wrapped upon itself as to produce a spirally extending joint 10 between the adjacent abrasive layers 11 and 12. The portion 12 engages upon the uncoated portion 15 of the next convolution 80 of material, and by spreading a suitable layer of adhesive upon this uncoated portion of the strip before the latter is thus wound, it is possible to produce a substantially integral spirally wound tube which may then be cut into cylindrical sleeves 16, 17, 18, etc., of any desired 85 lengths.

In Fig. 5 I have shown a modification of the sleeve previously described, this modification consisting in the use of a hollow tubular supporting mandrel 20 within the sleeve proper. The use 90 of this mandrel, while not necessary, is sometimes an advantage, both in the manufacture of the sleeve and also in its use. In manufacturing the sleeve it is of course necessary to use some sort of a removable mandrel on which to roll up the 95 abrasive strip, and if the permanent mandrel 20 is employed it can be used in long lengths, about which the strip can then be coiled and can be conveniently cut off at the same time as the strip. The mandrel may be formed of paper, cardboard 100 or similar inexpensive material. A further advantage in the manufacture of the sleeve with the use of the mandrel is that the uncoated edge portion 8 of the strip 1 may then be omitted, the abrasive strip being coiled spirally about the mandrel with the edges of adjacent convolutions in exact contact instead of overlapping as in the previous construction. Another advantage in the use of the sleeve of Fig. 5 is that when such a sleeve is used on an expanding mandrel of the 105 110

usual type the ends of the sleeve are expanded more than the central portion, producing a convex surface from end to end of the sleeve instead of a perfectly straight cylindrical surface as desired. With a pasteboard mandrel within the sleeve the expanding pressure is applied against the mandrel instead of against the sleeve proper and no unequal expansion can occur.

The present sleeve has the advantage over 10 those now manufactured of having a very much stronger joint between the adjoining portions than it is possible to secure in the tongue and grooved joints which are now commonly used. This joint is extremely strong and offers no objection in use since there is no extending projection or seam at the joint between adjoining convolutions. In manufacture, the present method presents several advantages, the most important of which is that sleeves may now be formed 20 continuously in long lengths of stock and by automatic machinery, after which the resulting long lengths may be cut into any desired lengths for various uses.

Other forms may be employed embodying the 25 features of my invention instead of the one here explained, change being made in the form or construction, provided the elements stated by any of the following claims or the equivalent of such

stated elements be employed, whether produced by my preferred method or by others embodying steps equivalent to those stated in the following claims.

I therefore particularly point out and distinctly claim as my invention:—

1. In a method of making a tubular abrasive element, the steps which consist in wrapping spirally upon a hollow mandrel an abrasive coated strip with the edges of adjacent convolutions in contact with each other, and securing said strip to said mandrel by interposing a layer of adhesive,

2. In a method of making a tubular abrasive element, the steps which consist in wrapping spirally upon a hollow mandrel an abrasive coated strip with the edges of adjacent convolutions in contact with each other, securing said strip to said mandrel by interposing a layer of adhesive, and then cutting cylindrical blanks from said wrapped mandrel.

3. An abrasive element comprising a hollow cylindrical mandrel and a spirally wrapped abrasive coated sheet adhesively secured to said mandrel and completely covering the outer surface thereof, the convolutions of said sheet having adjacent edges in contact without overflowing.

WILLIAM J. ELLIS.
